UNITED STATES PATENT OFFICE.

EDWARD JOHN RIDGWAY, OF STATEN ISLAND, NEW YORK.

DESIGN FOR A PLATE OR SIMILAR ARTICLE.

Application filed February 9, 1922. Serial No. 624. Term of patent 3½ years.

To all whom it may concern:

Be it known that I, EDWARD JOHN RIDGWAY, a subject of the King of Great Britain and Ireland, residing at Staten Island, in the county of Richmond, State of New York, have invented a new, original, and ornamental Design for a Plate or Similar Article, of which the following is a specification, reference being had to the accompanying drawing, forming part thereof.

Figure 1 is a plan view of a plate showing my new design applied thereto, it being understood that the design is repeated around the entire circumference of the article; and

Fig. 2 is a side elevation thereof, partially in section.

While the design is here shown applied to a plate, it is applied to articles of crockery and chinaware in general, and my invention is not limited to its application to a plate.

I claim:

The ornamental design for a plate or similar article as shown and described.

In testimony whereof I have signed my name to this specification.

EDWARD JOHN RIDGWAY.
